[54] **REDUCTION OF 2-ACYL-1-NAPHTHOLS TO
2-ALKYL-1-NAPHTHOLS**

[76] Inventor: **Robert Benson Fugitt**, 23 Alwyn
Road, Newark, Del. 19713

[21] Appl. No.: **781,105**

[22] Filed: **Mar. 25, 1977**

[57]

ABSTRACT

Hydrogenation of 2-acyl-1-naphthols at 200 to 1000 pounds per square inch and 115° to 200° C. in the presence of a copper chromite catalyst produces the corresponding 2-alkyl-1-naphthols. These compounds are useful in the synthesis of 2-alkyl naphthoquinone miticides.
